US00D976857S

(12) **United States Design Patent** (10) Patent No.: **US D976,857 S**
Lee et al. (45) Date of Patent: ** Jan. 31, 2023

(54) **STAND FOR TELEVISION RECEIVER**

(71) Applicant: **LG ELECTRONICS INC.**, Seoul (KR)

(72) Inventors: **Nari Lee**, Seoul (KR); **Woosuk Park**, Seoul (KR); **Sangik Lee**, Seoul (KR)

(73) Assignee: **LG ELECTRONICS INC.**, Seoul (KR)

(**) Term: **15 Years**

(21) Appl. No.: **35/512,560**

(22) Filed: **Mar. 16, 2021**

(80) **Hague Agreement Data**

Int. Filing Date: **Mar. 16, 2021**

Int. Reg. No.: **DM/213446**

Int. Reg. Date: **Mar. 16, 2021**

Int. Reg. Pub. Date: **Sep. 17, 2021**

(30) **Foreign Application Priority Data**

Sep. 23, 2020 (KR) 30-2020-0045976

(51) LOC (14) Cl. **14-03**

(52) U.S. Cl.

USPC **D14/126**; D14/239; D14/452

(58) **Field of Classification Search**

USPC D14/125-129, 132, 300, 308, 310, 316, D14/336, 357, 371, 375-380, 451, 452, D14/239; D26/93

(57) **CLAIM**

The ornamental design for a stand for television receiver, as shown and described.

DESCRIPTION

1. Stand for television receiver
- 1.1 : Right side perspective view
- 1.2 : Second right side perspective view
- 1.3 : Front view
- 1.4 : Left view
- 1.5 : Right view
- 1.6 : Top view
- 1.7 : Enlarged right side perspective view, taken from reproduction 1.1
- 1.8 : Exploded right side perspective view
- 1.9 : Rear view
- 1.10 : Bottom view
- 1.11 : Enlarged right side perspective view, showing the hinges in an alternate position
- 1.12 : Front view, showing the hinges in an alternate position
- 1.13 : Right view, showing the claimed design in an alternate position
- 1.14 : Top view, showing the claimed design in an alternate position
- 1.16 : Top view, showing the hinges in an alternate position
- 1.17 : Front view, showing the hinges in an alternate position
- 1.18 : Front view, showing the hinges in an alternate position
- 1.19 : Right side perspective view, showing the claimed design in an alternate position
- 1.20 : Right side perspective view, showing the claimed design in an alternate position

(Continued)

1.21 : Right side perspective view, showing the claimed design in an alternate position

1.22 : Right side perspective view, showing the claimed design in an alternate position

1.23 : Right side perspective view, showing the claimed design in an alternate position

The broken lines indicate portions of the article that form no part of the claimed design.

1 Claim, 22 Drawing Sheets

(58) Field of Classification Search

CPC G06F 1/1601; G06F 1/1605; G06F 1/162
